UNITED STATES PATENT OFFICE

165,910

LADY'S SOCK

Herman E. Crawford, Kernersville, N. C.

Application September 29, 1950, Serial No. 12,404

Term of patent 14 years

(Cl. D47—7)

To all whom it may concern:

Be it known that I, Herman E. Crawford, a citizen of the United States, residing at Kernersville, county of Forsyth, State of North Carolina, have invented a new, original, and ornamental Design for a Lady's Sock, of which the following is a specification, reference being had to the accompanying drawings, forming a part thereof.

The sock is characterized by the upper portion thereof being provided with a plurality of lines of loops of yarn, said lines extending generally wale-wise of the sock.

I claim:
The ornamental design for a lady's sock, substantially as shown and described.

HERMAN E. CRAWFORD.
